METHOD AND APPARATUS FOR RECOVERING CHEMICALS OF SULPHATE PAPER PULP

Norman A. Lewthwaite, Port Townsend, Wash., assignor to Crown Zellerbach Corporation, San Francisco, Calif., a corporation of Nevada

Application July 19, 1940, Serial No. 346,412

2 Claims. (Cl. 210—199)

My invention relates to soda, sulphate pulp, or similar processes for making wood pulp, in which the chemicals used are costly, and from which, therefore, the recovery of as much as possible of the reclaimable chemicals held by the pulp blown from the digester is exceedingly important.

Heretofore so-called "rotary vacuum filters" have been generally used for the purpose of such recovery. As well known, such a filter comprises a drum, the rim of which is covered with fine wire cloth and the drum is rotated in a vat filled with black liquor and pulp discharged from the digester. The interior of the drum of these rotary filters is divided into a series of consecutive, radially-disposed circumferential compartments or trays, into which the liquor removed from the sheet of pulp picked up by the drum is drawn, and conveyed to a suitable receptacle. It is customary to apply a shower to the sheet for aiding in the washing out of the liquor held by the sheet.

The rotary vacuum filter has one poor feature, namely the large reduction in the solids content of the liquor recovered, which reduction correspondingly increases the cost of evaporating the recovered chemical solution. To overcome such difficulty, these filters have been used in series, with the hot-water "shower" applied to the sheet of pulp carried on the drum of the last of the series of filters, and the filtrate obtained from the last filter, which is a "weak" liquor, being applied as a shower to the sheet of pulp formed on the preceding filter; and, in similar manner this procedure is carried on backward, through the series, if composed of more than two units of said filters.

Such arrangement effects decided improvement in the concentration of the liquor recovered; but the disadvantage of the arrangement is that it requires several filters and thus a large capital investment, as well as repumping between filters and the pumping of large volumes of filtrate.

The purpose of my invention is to provide an improved method to effect an efficient recovery of the chemicals with only a single rotary vacuum filter, that is, to obtain the same concentration of the solids content in the recovered liquor as obtainable from the employment of a series of filters, and in a more efficient manner. By my invention a substantial reduction in the high cost of installation and also in the cost of operation of a series of said filter units is made possible.

I discovered by extensive tests that if the full strength high-density black liquor is first removed from the initial portion of the sheet picked

up by the filter drum and separately collected and then the remaining portion of chemical solution held by the sheet is washed out by the application thereto for a limited time of a "weak liquor" wash and the two filtrates so obtained are then mixed, a much higher density liquor is recovered; and the cost of final evaporation of such liquor is greatly reduced.

The further details of my invention are hereinafter fully described with reference to the accompanying drawings:

In the drawings:

Figure 1 shows a diagrammatic elevation of the digester and the auxiliary devices customarily employed in producing paper-making pulp from wood by the soda process;

Figure 2 shows a diagrammatic perspective of the apparatus employed by me for practicing my invention;

Figure 3 shows a diagrammatic end-view of the drum of my rotary vacuum filter;

Figure 4 shows an end-view of the drum of my filter partly in section, and illustrates a specific construction of the interior of the drum which I found convenient to employ; and

Figures 5 and 6 show details of construction.

Referring first to Figure 1, a digester 1 empties into a blow tank 2, from which the pulp is carried by a pipe-line 3 to a vat 4, in which is rotated a filtering vacuum drum 5. The rim of the drum is understood to be covered with a filtering medium, for example, fine wire-cloth. The interior of the drum is divided into an endless series of compartments for receiving the filtrates drawn from the sheet of pulp through the filtering rim.

Preferably the arrangement of such compartments is as shown by 6 in Figure 4. These compartments are connected to spoke-like pipes 7, having outlets 8 located around the hub of the drum.

At one end of the drum 5 is provided a suction box 32 (Figs. 2, 5 and 6) having two arcuate vacuum chambers 33 and 34 enclosing, respectively, the outlets 8 (Fig. 4) of the drum when registering therewith during the rotation of the drum. The lower-level suction-pipe 9 connects with vacuum chamber 33 and the upper-level suction-pipe 10 connects with vacuum chamber 34. By this arrangement, as will appear, the filtration process carried on by the filter (Fig. 3) is divided into a relatively large zone 20 discharging through the vacuum chamber 33, for the removal of the full-strength high-density liquor held by the initial section of the sheet, and a smaller one 21 discharging through the vacuum chamber 34.

which serves for the removal of the remaining liquor from the sheet with the application of a shower. No vacuum is applied to the sheet while carried through the arcuate zone 31.

The lower-level suction-pipe 9 leads to strong liquor chest 12 (Figure 1). The upper-level suction-pipe 10 is connected to a receptacle 11. A vacuum is assumed to be maintained by suitable means (not shown) in the chambers 33 and 34 and in the suction pipes 9 and 10, and the receptacle 11. The described apparatus will be sufficiently understood by anyone practical in the art without giving further details thereof.

A shower 13 of weak liquor is applied to the sheet in the first zone 20. This shower, however, is located a predetermined distance from the boundary between zones 20 and 21 so that the weak liquor from this shower will not have time to penetrate entirely through the sheet before such showered sheet portion has reached the second zone 21. The shower 13 is supplied through the medium of pump 14 from the receptacle 11 containing the weak liquor filtrate obtained from the second zone 21.

A second shower of hot water is sprayed on the pulp sheet in zone 21 by spray pipe 30. The excess weak liquor filtrate from receptacle 11 passes through separator 16 and is finally intermixed with the strong liquor in chest 12. The air and vapor gases contained in receptacle 11 escape through pipe 11a to separator 16 which is connected with trap 17, and the latter is connected with vacuum chamber 18; and the apparatus is otherwise arranged in the customary manner, sufficiently indicated in Figure 1, without further description.

The second and final shower of hot water 30 washes the "weak-liquor" from the first shower 13 from the sheet and maintains the "weak liquor" in receptacle 11 in proper consistency. The hot water shower 30 must be controlled according to requirements.

The sheet of pulp 15, formed on the drum 5 is finally lifted from the latter by the customary doctor 22, and drops into a hopper 23 and is conveyed by conduit 24 to the vat 25 of a secondary rotary vacuum filter 26. The liquid here drawn from the pulp is discharged to the sewer because its chemical content is negligible.

The pulp, scraped off the secondary filter 26 drops into a hopper 27, which discharges into the pulp chest.

Naturally the distances and locations of the showers and boundaries of the vacuum zones 20 and 21 are not absolute, and should be changed for different speed of rotation of the drum, different thicknesses and characteristics of the pulp sheet, etc., in order to produce most efficient results.

By my method of procedure above described consisting in first withdrawing from the initial section of the sheet lifted from the vat 4 the full strength high-density liquor held by the sheet and separately collecting the filtrate so obtained, without permitting any dilution, then washing out the weaker liquor acquired by the sheet from the weak liquor shower, and finally permitting the overflow of recovered weak liquor to be added to the recovery of full-strength liquor, raises the

density of the black liquor to a much higher degree than that of the black liquor recovered the preceding process of procedure.

I claim:

- 5 1. In an apparatus of the character described including a pulp digester and a vat into which the discharge from the digester is received, combination of a rotary vacuum filter rotatable about a central axis, said filter being divided into an endless series of consecutive compartments for receiving the liquor abstracted from the sheet of pulp picked up by the filter from the vacuum chamber arranged to cover the compartments located in a zone of predetermined length through which zone the rising side filter travels, whereby the compartments in the zone and said vacuum chamber will receive liquor abstracted by the filter from the section of the sheet, means for separately collecting the liquor received from said vacuum chamber, a second vacuum chamber arranged to cover the compartments located in a second zone of predetermined length through which the filter travels after leaving the first zone during its complete rotation, means for applying a shower of liquor to said sheet while the filter travels through said first zone, said shower located a predetermined distance from the boundary between first and second zones to prevent the weak liquor from said shower from penetrating the sheet through said sheet before entry into said second zone, means for applying a second shower of water to said sheet in said second zone, a compartment between said second vacuum chamber and said means for applying said shower in said second zone whereby the filtrate obtained from said second vacuum chamber will constitute the liquor for said first-mentioned weak-liquor shower, means for separately collecting any excess filtrate from said second vacuum chamber which is not used for said weak liquor shower and combining said excess with the filtrate obtained in said first zone, whereby a high density resulting mixture is obtained.
- 10 2. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 15 3. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 20 4. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 25 5. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 30 6. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 35 7. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 40 8. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 45 9. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 50 10. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 55 11. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 60 12. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
- 65 13. In the described process for the recovery of chemicals from digester pulp through the use of a rotary vacuum filter, the improvement consists in withdrawing the filtrate from the sheet of pulp in a first area without diluting it, separately collecting such filtrate, withdrawing filtrate from the sheet of pulp in a second area located after said first area in the direction of rotation of said filter, applying a weak liquor shower to the pulp sheet in said first area at a predetermined distance from the boundary between the first and second areas in order to prevent penetration of the weak liquor through the pulp sheet before entry of the pulp sheet into the second area, applying a second shower of wash water in said second area, using the filtrate obtained in said second area for said weak liquor shower, and combining any excess of filtrate abstracted in the said second area and not used for said weak liquor shower with the filtrate withdrawn from said first area, whereby a high density is obtained in the resulting filtrate mixture.
